WASTE GAS BURNER

Oliver F. Campbell and William H. Decker, Whiting, Ind., assignors to Sinclair Refining Company, New York, N. Y., a corporation of Maine

Application March 15, 1950, Serial No. 149,797

11 Claims. (Cl. 158—115)

Our invention relates to an improved emergency waste gas flare and a safe and reliable method for burning waste combustible gases of widely varying heat content at widely varying rates of flow. It particularly provides economical and reliable means for the safe and smokeless combustion of large quantities of petroleum refinery gases during emergency or shutdown periods in the refinery.

Refinery evolution and the increasing attention of the public authorities to the problem of atmospheric pollution have combined to make the safe and effective disposal of waste refinery gases significant. The trend in refineries has been toward larger units increasing gas production, toward new processes such as catalytic cracking producing greater volumes of light gases and toward more processes handling and employing light gases. At the same time the dangers of smog and gaseous contamination of the atmosphere to health and the annoyance of smoke in the vicinity of cities have attracted the attention of public authorities and in some cases have invited restrictive regulation. The problem of providing for adequate disposal of refinery gases under varying refinery conditions is a severe one because gas storage space cannot economically be provided for all contingencies or even for peak production levels. If the waste gases are to be burned, they must be burned without substantial generation of smoke and without endangering refinery equipment or personnel. A flare designed to burn waste gases must be capable of handling quantities of gas varying from substantially zero flow to rates as high as 250,000 cubic feet per hour. The gas may vary in heat content from 500 B. t. u. to as high as 2,500 B. t. u. per cubic foot and may contain relatively high percentages of "wet" fractions. The gas may be at pressures ranging from approximately atmospheric to as high as 25 p. s. i. g. A useful waste gas flare must be capable of handling gases under these widely varying conditions and must be capable of burning such gases without generating appreciable quantities of smoke. Such a flare also must be low in cost and simple to construct and must be extremely rugged to stand up under sustained periods of high gas combustion rates. It must be substantially fool-proof in operation and should be provided with positive type ignition pilot burners which can be operated remotely.

According to our invention, we provide a burner assembly situated for the sake of safety at the end of an elevated gas pipe of large section. The burner assembly comprises a cap plate supported at a distance from the end of the pipe so as to provide a peripheral gas exit of greater area than the cross-sectional area of the pipe and further comprises a plurality of steam jets surrounding the gas exit. We have found that the available energy contained in the high pressure steam provides adequate mixing of the gases to be burned with combustion air so as to obtain substantially smokeless combustion by ejecting the steam at high pressure around the gas exit. Preferably, the ejection means comprises a steam ring which is perforated on its upper side so as to act as an aspirating device. The ejected steam then provides the necessary quantities of air and effects turbulent mixing of the air with the gases to be burned so that smokeless combustion results.

2

A metal shroud surrounding the burner assembly is provided to act as a partial mixing chamber. A flame arresting means is interposed in the gas pipe between the gas exit and the point of supply. A pilot burner system which can be operated remotely is provided in association with the burner assembly so as to insure positive ignition.

Our invention will be described by reference to the accompanying drawings. Figure 1 represents a view of a vertical type emergency gas burner in side elevation with parts broken away or inverted. Figure 2 represents a section upon the lines 2—2 of Figure 1. Figure 3 represents an enlarged view of the upper portion of the burner including the burner assembly partly in section along lines 3—3 of Figure 4. Figure 4 represents a top plan view of the burner assembly. Figure 5 represents an enlarged view of a portion of the pilot burner assembly visible in Figure 3. Figure 6 is a sectional view taken along lines 6—6 of Figure 5.

10 The emergency gas burner advantageously is a tall vertically elongated structure for purposes of safety but where space permits, it may be horizontally disposed, advantageously adjacent a fireproof target wall. In the burner illustrated in the drawings the main flare pipe 10 consists of a 30-inch standpipe 10, approximately 90 feet in elevation. The gas standpipe 10 is arranged on a swivel base 11 so that it may be lowered for maintenance and repair purposes. As shown, a lower pipe section 12 is also provided which is mounted on a second swivel base 13. Gas from the refinery collecting system is supplied to the gas standpipe 10 through section 12 and through gas main 14.

20 A flame arrestor designed to prevent flareback of gases is situated on top of the standpipe 10 and is housed in section 15. The flame arrestor may consist of a series of interlocking bars forming a large area of cooling surface. A second standpipe or flare pipe 16, 25 inches in diameter by approximately 10 feet high, is mounted on top of the flame arrestor housing 15. The top of the flare pipe 16 is capped with a flat circular plate 17 supported at its periphery by steel strips or slats 18, 6 inches in length arranged so that the open area between the supporting strips is slightly greater than the area of the flare pipe 16 itself. The structure of the cap plate 17 and supporting strips 18 is better seen in Figures 3 and 4. Advantageously, the supporting slats 18 of the burner assembly are set at an angle of approximately 45° so that a tangential swirling motion is imparted to the released gases which will aid considerably in mixing the gases with the incoming air. The top of the cap plate 17 advantageously is protected from high temperatures by application of a plastic refractory material. At the elevation of the burner end of flare pipe 16, a steel shroud 19 is mounted by means of gusset plates 20. As shown shroud 19 is 5 feet in diameter and extends 1 foot 7 inches above the end of flare pipe 16. The steel shroud is designed to protect the burner proper from wind currents and at the same time to provide a partial mixing chamber for the gas and air. At the elevation 30 of the gas exit formed by the supporting strips or slats 18 and cap plate 17, a 2-inch steam ring 21 is installed. The ring as shown is approximately 4 feet in diameter and is supported by gusset plates 20. The steam ring 21 is drilled along its upper surface with seventy-two $\frac{1}{8}$ -inch holes to provide for the injection of high pressure steam supplied through a 2-inch steam line 22. Steam line 22 is insulated and connected by flexible connection 23 and connection 24 to a steam header 25. Steam flow may be controlled by means of block valve 26. Advantageously turbulent mixing of air with the release gases is promoted by drilling the injection holes in steam ring 21 so that they are slanted in the same

direction as the supporting strips or slats 18 in the gas exit area.

The pilot burner assembly comprises three 4-inch pilot guide pipes 27 which are symmetrically arranged around flare pipe 16 with their upper ends flush with the bottom of the gas exit in the burner assembly. The pilot guide pipes 27 are each provided with a 1-inch slot 28 extending its entire length and opening outwardly from the center of the burner. The details of the pilot burner assembly are better seen in Figures 3, 4, 5 and 6. The lower end of the pilot guide pipes 27 is covered by a conical steel shield 29 to protect spark igniters 30 from direct flame impingement or flame radiation. Spark igniters 30 are high tension spark plugs mounted in opposing pairs in each of the pilot guide pipes 27 approximately 6 inches from the lower end. The spark igniters 30 are tied to high tension transformer boxes (not shown) and a remotely located push button station is provided for spark ignition. In the center of each of pilot guide pipes 27 is installed a single $\frac{3}{4}$ -inch John Zink type ST pilot burner 31. This burner is a simple air-mixing type gas jet and each pilot burner 31 is provided with a pre-mixing chamber 32 below the bottom end of each pilot guide pipe 27. The burners of pilot 31 are located approximately 6 inches below the top end of the pilot guide pipes 27. Each of the three pilot burners 31 is connected through gas supply ring 33 to a single gas supply header 34 which is provided with a block valve 35 at the base of pipe 12 for remote operation. In order to provide for ignition of pilot burners 31 each of the individual pilot guide pipes 27 is supplied with three $\frac{1}{4}$ -inch pipe leads 36 through a header 37 and ring gas supply pipe 38, which is supplied through 1-inch gas line 39. Gas line 39 is provided at the base of standpipe 12 with a flexible connection 40 and may be controlled remotely by block valve 41. The pipe leads 36 are arranged so that they project through the 1-inch slot 28 in pilot guide pipes 27 and are spaced approximately equi-distant along the length of pilot guide pipes 27.

In order to place the burner in operation, the spark igniter circuit is closed, and the gas supply block valve 41 to pilot guide pipes 27 is opened. As soon as ignition is assured, as may be seen by flame covering the entire length of pilot guide pipes 27, the gas supply of block valve 35 to pilot burners 31 is opened. When it is evident that pilot burners 31 are in service, the block valve 41 controlling the pre-ignition gas flow to pilot guide pipes 27 is turned off. At the same time the igniter circuit is open since there is no need to maintain continued excitation of the spark plug. The burner is now ready for emergency firing of dump gases. When flaring begins, the block valve 26 supplying steam to steam aspirating ring 21 is opened slowly and is adjusted so that the rate of steam flow is such as to provide for smokeless combustion. The quantity of steam required is a function of the quantity of gas being burned, the B. t. u. value of the gas and the pressure head of the dump gases. If at any time during actual operation, pilot burners 31 are extinguished, the ignition process is repeated. In test operation, it has been found that the burner may be readily ignited by employing the pilot burner system of our invention and that the pilot flames are stable and apparently unaffected by high wind or heavy rain conditions. Thus, positive ignition of the main dump gas stream is assured. At the initiation of the test run, gas was released from the main refinery gas holder at a rate of about 130,000 cubic feet per hour. At the start no steam was used and tremendous quantities of heavy black smoke were produced. When steam was admitted to the steam ring, the smoking condition cleared up very quickly. Satisfactory mixing was shown by the fact that it was almost impossible to directly observe the flame, and the flame produced was excessively bright without smoke. During the test period, approximately 4,200 to 4,500 pounds per hour of 125 pounds steam were em-

ployed for the dumping rate of 130,000 cubic feet per hour. The gas was estimated to have a B. t. u. value of approximately 1,300 B. t. u.'s per cubic foot. The gas was supplied to the burner at a pressure of only several inches of water from a water-sealed gas holder. Our invention provides a simple, safe and reliable system for assuring smokeless combustion of refinery gases under emergency dumping or waste flaring conditions by utilization of the energy content of high pressure steam or other gas to supply the desired amount of combustion and assure turbulent admixture. Our invention provides a burner and method of operation that assures substantially smokeless combustion over a wide range of gas rates from substantially zero flow to as high as 250,000 cubic feet per hour or more. Gases ranging in B. t. u. content from 500 B. t. u. to 3,000 B. t. u. per cubic foot are equally well handled, and operation is satisfactory over a range of a few ounces to 25 p. s. i. g. or more. Thus a means is provided for emergency disposal of gases in the event of emergency shutdown of a cracking unit or in the event of a sudden drop in the normal burning capacity of the refinery so that the refinery gas holders are overloaded and their water-seals broken through gas overflow. On the other hand, our invention provides a useful means for disposing of small amounts of gas vented into the refinery gas system during the usual daily testing of safety valves in units such as propane solvent treating where large quantities of gas under high pressure are employed.

The combustion of gases according to our invention is for all practical purposes instantaneous so that close adherence to existing smoke regulations is assured. Because of the simplicity of the burner, it is simple to construct at low cost. The use of high alloy materials may be avoided by the use of suitable plastic refractory materials since all metal surfaces exposed to flame radiation or flame impingement may be readily protected. The arrangement of the pilot assembly is such that none of the parts of the burner assembly are exposed to continuous flame impingement of the pilot burners. Long time operation and minimum maintenance care result. Because of the inherent simplicity of the burner, its operation is reliable and virtually fool-proof. It may be operated remotely from any location. For example, the unit may be provided with a pilot-operated control valve in the steam or air or gas supply line so that when flaring commenced the steam or air or gas required could be supplied in direct relationship to the amount of gases to be burned. Such a control valve may be operated by pressure, by flow or by a combustion control means such as a flame detector or haze gauge. The burner requires very little ground space and may be adapted to installation on top of various structures, such as large refinery stills or buildings. The burner may be located however at grade in a horizontal position. A number of smaller units firing into a target wall may be employed. Obviously a number of changes may be effected in the burner design and method of operation we have described.

For example, a plurality of steam rings or a plurality of steam supply pipes to the steam ring may be employed to obtain improved mixing and pressure control. Instead of a circular steam ring, a plurality of individual small venturi sections may be arranged symmetrically around the gas exit area. The venturi sections may be supplied by individual small steam supply lines. Also the metal shroud section surrounding the burner assembly may be constructed with advantage in the form of a large venturi section in order to assist in supplying air to the burner proper. Combustion air or gas could be employed in place of the steam mixing medium.

We claim:

1. An emergency gas flare which comprises an elongated gas pipe; a burner assembly comprising a cap plate

supported at a distance from the end of the pipe so as to provide a peripheral gas exit of greater area than the cross-sectional area of the pipe, and a plurality of steam jets positioned around said end of said pipe and directed across the path of gas flowing from said gas exit; an open ended shroud of closed side wall construction having a section larger than said gas pipe mounted coaxially therewith and surrounding the burner assembly, the inner end of said shroud being positioned inwardly of the outer end of said gas pipe and the outer end of said shroud being positioned outwardly of said cap plate; flame arresting means interposed in the pipe between the gas exit and the point of gas supply; means for supplying steam to said steam jets; and a pilot burner assembly comprising at least one open ended pilot guide pipe mounted lengthwise of said gas pipe with the outer end of said guide pipe adjacent said peripheral gas exit and positioned between said gas pipe and said steam jets and with the inner end of said guide pipe positioned inwardly of the inner end of said shroud, a slot in said guide pipe extending lengthwise thereof and opening outwardly from said gas pipe, and pilot flame ignition means mounted in said guide pipe including a pilot burner at the outer end of said guide pipe, means for supplying gas to the inner end of said guide pipe, and spark ignition means at the inner end of said guide pipe for ignition of gas in said guide pipe.

2. The gas flare of claim 1 in which the plurality of steam jets of the burner assembly represent a perforated ring pipe surrounding the gas exit.

3. The gas flare of claim 1 in which the cap plate is supported by a plurality of spaced slats set at an angle of approximately 45° with a plane through each slat and the axis of the gas pipe.

4. The gas flare of claim 1 in which the shroud is constructed in the form of a venturi section surrounding the burner assembly.

5. An emergency gas flare which comprises an elongated gas pipe; a burner assembly comprising a cap plate supported at a distance from the end of the pipe so as to provide a peripheral gas exit of greater area than the cross-sectional area of the pipe and a plurality of steam jets positioned around said end of said pipe and directed across the path of gas flowing from said gas exit; an open ended shroud of closed side wall construction having a section larger than said gas pipe mounted coaxially therewith and surrounding the burner assembly, the inner end of said shroud being positioned inwardly of the outer end of said gas pipe and the outer end of said shroud being positioned outwardly of said cap plate; flame arresting means interposed in the pipe between the gas exit and the point of gas supply; means for supplying steam to said steam jets; a pilot burner assembly comprising a plurality of open ended pilot guide pipes mounted lengthwise of said gas pipe and symmetrically disposed about said gas pipe with the outer end of each of said guide pipes adjacent said peripheral gas exit and positioned between said gas pipe and said steam jets and with the inner end of each of said guide pipes positioned inwardly of the inner end of said shroud, a slot in each of said guide pipes extending lengthwise thereof and opening outwardly from said gas pipe, pilot flame ignition means mounted in each of said guide pipes including a pilot burner at the outer end of said guide pipe, spark ignition means at the inner end of said guide pipe for ignition of gas in said guide pipe, means for supplying gas to the inner end of said guide pipe, means for supplying gas intermediate the length of said guide pipe, and a shield mounted around the gas pipe for covering the spark ignition means.

6. An emergency gas flare which comprises a vertically elongated gas standpipe mounted on a swivel base; flame arresting means mounted on the standpipe; a vertically elongated flare pipe mounted on the flame arresting means; a burner assembly comprising a cap plate supported up-

wardly from and transversely to the end of the flare pipe so as to provide a peripheral gas exit of greater area than the cross-sectional area of the pipe and a plurality of steam jets positioned around said end of said pipe and directed across the path of gas flowing from said gas exit; an open ended annular shroud of a diameter larger than said flare pipe mounted coaxially therewith and surrounding the burner assembly, the inner end of said shroud being positioned inwardly of the outer end of said gas pipe and the outer end of said shroud being positioned outwardly of said cap plate; means for supplying steam to said steam jets; and at least one open ended pilot guide pipe mounted lengthwise of said gas pipe with the outer end of said guide pipe adjacent said peripheral gas exit and positioned between said gas pipe and said steam jets and with the inner end of said guide pipe positioned inwardly of the inner end of said shroud, a slot in said guide pipe extending lengthwise thereof and opening outwardly from said gas pipe, and pilot flame ignition means mounted in said guide pipe including a pilot burner at the outer end of said guide pipe, spark ignition means at the inner end of said guide pipe for ignition of gas in said guide pipe, means for supplying gas to the inner end of said guide pipe, and means for supplying gas intermediate the length of said guide pipe.

7. An emergency gas flare comprising a gas pipe for conducting waste gas; a burner assembly mounted on said gas pipe having a cap plate supported outwardly of the outer end of said gas pipe and transversely thereto to provide a peripheral gas exit of greater area than the cross-sectional area of the pipe, and aspirating means positioned at and around said outer end of said gas pipe and directed to eject a fluid across the path of waste gas flowing from said peripheral gas exit; and an open ended shroud having a closed side wall forming a mixing chamber surrounding said burner assembly and said gas pipe, the inner end of said shroud being positioned inwardly of the outer end of said gas pipe and the outer end of said shroud being positioned outwardly of said cap plate.

8. An emergency gas flare in accordance with claim 7 in which the aspirating means includes a perforated ring pipe surrounding the peripheral gas exit.

9. An emergency gas flare in accordance with claim 7 in which the cap plate is supported by a plurality of spaced slats set at an angle of approximately 45° with a plane passing through each slat and the axis of the gas pipe.

10. An emergency gas flare in accordance with claim 7 in which the shroud is constructed in the form of a venturi section surrounding the burner assembly.

11. An emergency gas flare in accordance with claim 7 and including a pilot burner assembly comprising an open ended guide pipe mounted lengthwise of said gas pipe with its outer end adjacent said peripheral gas exit positioned within the space enclosed by said shroud and with its inner end positioned inwardly of the inner end of said shroud, a pilot burner positioned at the outer end of said guide pipe, and a slot extending lengthwise of said guide pipe and opening outwardly from said gas pipe.
